KARL MENSING, OF HANAU-ON-THE-MAIN, GERMANY.

QUARTZ LAMP.

Application filed August 24, 1921. Serial No. 494,947.

To all whom it may concern:

Be it known that I, KARL MENSING, a citizen of the German Republic, residing at Hanau-on-the-Main, Germany, have invented certain new and useful Improvements in Quartz Lamps; and I do hereby declare the following to be a full, clear, and exact description of the invention, such as will enable others skilled in the art to which it pertains to make and use the same.

The present invention relates to quartz lamps or lamps employing mercury vapor in their light emitting portion, and has to do particularly with the construction and arrangement of the electrode chambers provided at either end of the body portion of the lamp.

Successful operation of lamps of this type has been attained by the so-called high pressure method. That is, the applied voltage is relatively high and, after an ignition period lasting approximately from ten to fifteen minutes during which the efficiency of operation is relatively low, the lamp will operate continuously with minimum power consumption and at maximum efficiency. A serious objection to this type of lamp, however, is the extent of the ignition period during which time the illumination of the lamp is very poor and only gradually increases to its proper value.

It is accordingly a principal object of the present invention to provide a quartz lamp of the above type in which the duration of the ignition period may, in comparison with the lamps hitherto in use, be materially diminished, in fact be reduced by more than one half.

The invention is based on the principle that the satisfactory and final economy value in quartz lamps operated by the high pressure method is not attained till the pressure of the vapor is sufficiently high, but the vapor pressure is in turn a function of the temperature of the mercury; that is, it rises in accordance with the degree to which the mercury is heated. In order to attain a high vapor pressure within the lamp as rapidly as possible it is necessary that the quantity of mercury contained in the lamp be heated as quickly as possible. I have found that this effect may be secured by employing a smaller quantity of mercury than is commonly used, by reason of which it is possible to effect a reduction in the length

of the ignition period of approximately one half.

The invention is based on the principle that the maximum efficiency of the lamp is not attained until the vapor pressure of the mercury reaches a certain value, and that this specified vapor pressure is dependent upon the temperature of the mercury and is not attained until the temperature of the body of mercury within the lamp is sufficiently high.

The reduction in the quantity of mercury cannot, however, be effected directly as by merely diminishing the size of the ordinary electrode chambers, since such reduction would result in a restriction of the cooling surfaces. In order to keep the electrodes at a sufficiently low temperature it is necessary that the same cooling area be presented as would be the case if the quantity of mercury were not reduced.

According to my invention the mercury within the cathode vessel is formed into a thin layer adjacent the inner surfaces of the vessel, preferably by spacing within the vessel a quartz tube which almost completely fills the space available. The anode vessel is supplied with only a small quantity of mercury and is preferably provided with a small cavity or depression near its point of attachment to the body of the lamp, the volume of the cavity being substantially equal to the volume of mercury necessary to effect the ignition of the lamp by tilting.

Reduction of the quantity of mercury, besides having the effect of shortening the ignition period, has the further substantial advantage that the risk of breakage from impact of the mercury during transport is greatly reduced, since the masses are much smaller. This advantage is still further enhanced by the shape of the electrode vessels employed, especially by that of the cathode vessel.

The drawings represent by way of example certain constructional forms of burners for quartz lamps, according to the invention.

Fig. 1 is a longitudinal sectional view of a quartz lamp and its electrode chambers embodying my invention; Fig. 2 is a sectional view through the cathode vessel taken on line 2-2 of Fig. 1; Fig. 3 is an elevational view looking from the left of Fig. 1, and showing the construction of the anode

chamber; Fig. 4 is a longitudinal sectional elevation showing a modified form of anode vessel; Fig. 5 is a view taken on line 5—5 of Fig. 4; and Fig. 6 shows performance curves typical of a quartz lamp embodying my invention.

In the burner tube *a* of Fig. 1, *A* is the anode and *K* the cathode, the latter consisting as is usual of a vessel *b* disposed transversely to the burner-tube *a* and having a precisely similarly shaped shallow quartz tube *c* closed at the end, disposed within it, which, in the example shown in the drawing, is kept at a distance from the internal wall 10 of the vessel *b* by means of fused quartz projections *d*. The intervening space between *b* and *c* is filled with a thin layer of mercury, the thickness of which depends merely on the length of the studs *d* and on the exactitude of the finish of the parts fitted into each other. In any case, this space is very small. The cathode vessel *K* is formed integrally with the body portion *a* of the lamp, 15 communication between the two parts being established by a passage *f* of diameter less than that of the body portion *a*. The reduction in the diameter of the passage *f* is preferably accomplished by increasing the thickness of its walls as shown. This 20 passage of reduced section is especially valuable in exerting a retarding effect upon the flow of mercury when the lamp is tilted, thus minimizing the danger of breakage due to a sudden rush of the mercury from 25 one part of the tube to another. The entire volume of the chamber is free from obstruction and consequently permits free circulation of the mercury, thus securing an advantage not obtained in case the reduction of 30 the volume of mercury is effected by partially filling up the anode chamber with irregular bodies such as quartz chips or the like. 35

As may be seen from Fig. 1 the anode vessel *A* is provided in the center with a small depression *g*, of such volume that it contains exactly the amount of mercury necessary for ignition by tilting. It is convenient to give the vessel the form shown in Fig. 3. It is preferably not constructed 40 of cylindrical form as commonly done, but rather the two halves are inclined slightly upward so that a depression *g* is created in the middle. The mercury which condenses on the walls of the vessel will thus collect 45 and drain into the deeper part of the depression.

I have found it desirable to integrally attach the body portion *a* to the anode chamber at its upper central portion, as 50 shown in Fig. 1, the cross sectional area of the body portion being uniform throughout its length. Approximately at the junction point between the two members I preferably insert a small plate *h* of quartz or similar 55 material at an angle of about 45° to the

longitudinal axis of the lamp for the purpose of exerting a steady influence upon the electric arc, and also serving as a means for absorbing the impact of the mercury rushing from one end of the tube to the other, and thus rendering breakage of the tube unlikely.

Instead of the connection between the anode vessel and the body portion *a* being of uniform cross-section equal to that of the body portion and an auxiliary plate *h* being employed, as above described, a construction may advantageously be employed in which the light emitting tube may, adjacent to the anode, have its walls rounded and thickened as shown in Fig. 4, similarly to the cathode passage *f*. The anode and cathode parts acquire thus, at the same time, a symmetrical form that is favorable to manufacture since both the anode and cathode parts may be made with identical manufacturing methods. There is, however, provided on the anode a connecting tube *z* of small diameter for equalizing the distances in vapor pressure which may arise between the light emitting tube and the hollow space in the anode vessel. When the anode vessel is constructed in this way it may also be placed in a vertical position, as in Figs. 4 and 5. *A*¹ here denotes the upstanding anode vessel, *f*¹ is the reduced junction of the light-emitting tube corresponding to that on the cathode side, and *z* is the equalizing tube.

As will be evident at once from a glance at the drawing, not only is the requisite quantity of mercury reduced to a minimum with this new burner, but, at the same time, the danger of breakage by blows from the mercury is actually avoided. The narrow cross sections of the cathode vessel will obviously tend to counteract movement and the same is true of the narrow part *f*¹, or the plate *h* in the anode vessel, the latter constituting an impact plate for the deflection and fine division of the mercury.

The diagram of Fig. 6 represents graphically the operation of a quartz lamp embodying my invention as compared with that of a lamp of ordinary construction. In the diagram horizontal distance represents time. The curves *V*⁰ and *J*⁰ represent, respectively, the variation in voltage and current in a quartz lamp of ordinary construction beginning with the time that current is first switched on. It is to be noted that at first the current values *J*⁰ are relatively high and only gradually recede to their final value after a period of almost fifteen minutes. The voltage, likewise, increases but slowly and does not attain its final value until almost fifteen minutes after the current first flows. The curves *V* and *J*, respectively, represent the voltage and current values in a typical lamp embodying my invention. It

is seen that the current drops rapidly and attains its final value in a relatively short time after the beginning of the ignition period, while the voltage attains its final value in a like time, which I have found to be about five minutes. The lamp thus reaches its maximum efficiency and illumination output in a length of time which is ordinarily from five to ten minutes less than that required by lamps in common use at present.

While I have described and illustrated a preferred embodiment of my invention, it is to be understood that the construction may be varied within the full scope of the appended claims.

I claim:

1. A quartz lamp of the class described comprising a chamber for containing the mercury and an element of relatively low specific heat occupying a substantial portion of the space within said chamber and spaced from the walls thereof, the mercury occupying the remainder of the space whereby in a mercury chamber of given external dimensions the total quantity of mercury is materially diminished without diminishing the heat transferring surface of the lamp.

2. A quartz lamp comprising an electrode vessel, an element of poor heat conducting properties disposed within said vessel and spaced from the walls thereof to thereby form a mercury chamber of relatively small volume adjacent the walls of the vessel

whereby the mercury is distributed to present a large superficial area adjacent the heat transferring surface of the lamp to thereby reduce the ignition period of the lamp to from 5 to 8 minutes.

3. A vapor electric device comprising an electrode vessel having a body of mercury therein, and an element of relatively low specific heat positioned to displace some of said mercury while leaving a substantially unrestricted passage between the wall of the vessel and said element, thereby forming a mercury chamber of relatively small volume within said vessel and distributing the mercury in a relatively thin layer adjacent the inner surfaces of said electrode vessel.

4. A quartz lamp, comprising a cathode vessel, an evacuated quartz tube occupying a large part of the space within said vessel, and means for maintaining said tube uniformly spaced from the inner walls of said vessel, thereby forming a mercury chamber of small volume and ample radiating surface between said vessel and tube.

5. In a quartz lamp, comprising a cathode vessel, an evacuated quartz tube occupying a large part of the space within said vessel, and fused quartz projections interposed between said tube and the inner wall of said vessel, thereby constituting a mercury chamber of small volume and uniform depth.

In testimony whereof I affix my signature.
KARL MENSING.
